UNITED STATES PATENT OFFICE

HECTOR RABEZZANA AND DONALD W. RANDOLPH, OF FLINT, MICHIGAN, ASSIGNEES
TO A C SPARK PLUG COMPANY, OF FLINT, MICHIGAN, A COMPANY OF MICHIGAN

SPARK PLUG

Application filed November 13, 1925. Serial No. 68,809.

One of the chief problems involved in the design of spark plugs for use in high compression engines such as are employed in racing machines and aeroplanes is that of disposing 5 of the heat which is absorbed by the lower portions of the central electrode and the surrounding insulator. If this heat is not rapidly carried away such high temperatures will soon be built up in the insulator that its 10 electrical resistance will be reduced and it may even become red hot and cause pre-ignition of the explosive mixture. As the portion of the insulator adjacent the central electrode is the hottest part of it, it is particularly 15 essential that this electrode be well cooled.

In this application we have disclosed a new design of plug which has for its purpose the overcoming of the difficulties above described. To facilitate the transfer of heat away from 20 the lower portion of the central electrode, thereby reducing the amount of heat passing from the electrode to the insulator, we have made this electrode very short so that the path of travel of heat to the cooled upper portion 25 of the electrode is reduced to a minimum. We have also preferably provided the electrode with cooling means which may consist of spaced fins extending outwardly from the plug and subject to the cooling effect of air 30 conduction or air draft.

As another means of assisting in the cooling of the plug we have thickened the portions of the shell which form the path for the conduction of heat from the insulator to the 35 cooler portions of the motor. By thus broadening the path for the conduction of heat, the rate of flow is increased.

With the construction so far described we have preferably combined the feature of employing an insulator having a ground, conical-shaped lower portion adapted to closely fit in a conical seat in the shell, as described and claimed in my prior application Serial No. 749,414 filed Nov. 12, 1924. We have thus 40 secured much better contact between the insulator and the shell thereby reducing the resistance to the flow of heat.

Referring to the drawings:

Figure 1 is a longitudinal sectional view of 50 one form of my improved spark plug;

Figure 2 is a section on line 2-2 of Figure 1;

Figure 3 is a view showing a slight modification of the construction of Figure 1;

Figure 4 is a longitudinal sectional view of 55 a modified form;

Figure 5 is a top plan view of Figure 3; and

Figure 6 is a section on line 5-5 of Figure 3.

The preferred form of our improved spark 60 plug is shown in Figures 1 and 2. In these figures the reference character 2 indicates the insulator which is mounted within the shell 4. Passing centrally through the insulator is the electrode 6 while the cooperating electrode 8 65 is mounted on the shell in any preferred manner.

A distinguishing feature of this plug is the shortness of the central electrode and insulator for purposes of cooling. To increase the 70 rate of cooling the upper end of the electrode is provided with special cooling means which may consist of fins or disks 10 exposed to the air currents. While the fins may be secured on the electrode by any preferred method or 75 may be formed integrally with the electrode, we have illustrated a construction in which the disks are slipped over the upper end of the electrode with spacing collars between them and are secured in position by a clamp- 80

ing nut 14. Preferably the disks and collars are provided with radial grooves 15 and 15' and in the assembly of the plug rings of solder, preferably of silver composition, are slipped over the collars 12, the whole being 85 then subjected to a heating operation which results in a flow of the solder along the radial passages 15 and 15', thus secured the disks to the electrodes 6 in good heat conducting relation. Of course, if preferred, the fins may 90 be secured in place by brazing or welding.

The electrode is also preferably formed of two metals, the lower portion 16 which is made of nickel or some other material which is not subject to corrosion being welded or 95 otherwise secured to the upper portion 18 which may be of copper or some other metal which is a good conductor of heat. If preferred, the electrode may be made entirely of some good heat conducting material such as 100

copper, provided at its lower end with a coating of a material such as platinum or the like, which is capable of successfully resisting deterioration when subject to combustion chamber conditions.

5 It will be noted that the portion of the insulator between the upper edge of the shell and the central electrode is formed with an upwardly extending annular rib 20 to increase the length of the path of travel for leakage currents which follow the surface of the insulator. This rib defines a depression 21 in the upper portion of the insulator permitting the cooling air currents to strike the 10 electrode further down in its length thus permitting a further effective reduction in the length of the said electrode. It will be noted that the fins or disks 10 are upwardly flared to conform to the flaring of the inner surface 15 of the rib 20.

To increase the rate of cooling we have employed, in addition, the feature of forming a very close fit between the lower portion of the insulator and the shell so that 25 heat will be rapidly conducted away from the former. Thus the lower portion of the shell is provided with a conical seat 22 receiving the conical portion 24 of the insulator without the interposition of the usual gasket. 30 This provides an extended contact area and eliminates one of the joints across which the heat must travel in the ordinary plug.

It will also be noted that we have thickened the lower portion 26 of the shell which 35 contacts with the cylinder head or other part in which the plug is mounted. This has the effect of broadening the path traversed by the heat as well as affording a greater mass of material for the absorption thereof with 40 the result that cooling is facilitated. This cooling action is rendered effective by the fact that the central electrode projects into a space inside the shell in which there is very little circulation of gases so that heat withdrawn 45 from said space is but slowly replaced. Consequently, by providing for the removal of heat at an increased rate equilibrium of heat flow is established at a lower temperature than with previous constructions. While in 50 this form we have provided for the increased rate of removal of heat merely by thickening the walls of the surrounding shell, we may also resort to grooving or serrating the said walls as illustrated in connection with the 55 construction shown in Figures 4 to 6, this feature forming the subject matter of my prior application Serial No. 44,867, filed July 20, 1925.

With a plug made as above described it 60 will be apparent that cooling of the hottest portion thereof, that is, the lower part of the central electrode and the lower part of the insulator is facilitated by shortening the insulator and the said electrode, by providing 65 the latter with cooling fins, by providing bet-

ter contact between the insulator and the shell and by thickening the lower portion of the latter. We have found by actual experiment that a plug made in this manner may be maintained at a lower temperature when subjected to extreme heat than any plugs heretofore designed.

70 While we have attempted to explain the causes which have produced this result it is not possible to ascertain with accuracy the exact heat relations which obtain in the plug and we accordingly do not wish to be limited by the statement of theory herein set forth.

75 The construction shown in Figures 1 and 2 may be modified as shown in Figure 3 by the interposition of the gasket 50 between the porcelain and the shell. The use of a gasket such as shown avoids the necessity for such exactness in the grinding of the contacting portions 22 and 24 of the shell and insulator. 80 While the gasket 50 might be in the form of a frusto-conical band of uniform thickness we have preferred to illustrate a gasket having portions of reduced thickness between its 85 ends, said portions contacting only with the inner wall of the shell. We are thus enabled to increase the pressure per unit area between the contacting surfaces of the gasket and insulator, a feature disclosed and claimed in the application of Albert Champion, Serial 90 No. 19,345, filed March 30, 1925. If desired, the intermediate portion 52 of the gasket 50 may be omitted.

95 In the modified form shown in Figures 4 to 6, 30 indicates the insulator, 32 the shell, 100 34 the central electrode, 36 the side electrode. In this form of the invention gaskets 38 are provided between the insulator and the lower portion of the shell. The interior of this portion of the shell is also preferably provided with ribs 40 as previously described. 105 In this embodiment the cooling fins 42 are integral with the electrode.

110 In this type of plug the central electrode is better insulated to prevent the plug from becoming too easily fouled.

We claim:

115 1. A spark plug comprising a shell, an insulator in the shell, an electrode passing through the insulator, said electrode being modified from standard practice in that it is relatively short to permit rapid conduction of heat therefrom, the lower portion of said shell being in good conducting relation with the insulator, and with the engine, said lower portion being of increased thickness for the ready transfer of heat, said electrode being provided with heat-radiating fins at its upper portion.

120 2. A spark plug comprising a shell having a conical seat, an insulator having a conical lower portion for engagement with said seat, an electrode passing through the insulator, said electrode being modified from standard practice in that it is relatively short to afford 125 130

a good path for the conduction of heat therefrom, the lower portion of said shell which is in good conducting relation with the insulator and with the engine being of increased thickness to facilitate the transfer of heat.

5. 3. A spark plug comprising a shell having a conical seat between its ends, an insulator having a conical lower portion in direct engagement with said seat, an electrode passing through said insulator, the ends of said electrode and insulator stopping short of the lower end of the shell, an electrode carried by the shell and extending inwardly from the lower end thereof, said first-named electrode being modified from standard practise in that it is relatively short to afford a good path for the conduction of heat from the lower end thereof, and cooling ribs carried by the upper end of said electrode.

20. 4. A spark plug comprising a shell having a conical seat between its ends, said shell being provided with a thickened lower end having external threads thereon, an insulator having a conical lower portion in direct engagement with said conical seat, an electrode passing through said insulator, the ends of said electrode and insulator stopping short of the lower end of the shell, an electrode carried by the shell and extending inwardly from the lower end thereof, said first-named electrode being modified from standard practise in that it is relatively short to afford a good path for the conduction of heat from the lower end thereof, said insulator being provided 35 at its upper end with a rib to increase the surface insulation.

5. A spark plug comprising a shell, an insulator in the shell, an electrode passing centrally through the insulator and being provided at its upper end with a cooling fin wholly clearing the insulator and directly exposed to the cooling action of passing air currents, said electrode being made of good heat conducting material solid in cross-section to permit maximum heat transfer, and said electrode and insulator being modified from standard practice in that they are relatively short so that the difference in temperature between the electrode at the cooling fin and the surrounding atmosphere is sufficiently great to permit effective cooling.

40. 6. A spark plug comprising a shell provided with the usual side electrode, an insulator in the shell, said insulator being relatively short and having its upper end projecting a slight distance above the upper end of the shell, said upper end of the insulator being provided with a protuberant rib to increase the surface insulation, an electrode passing 45 centrally through the insulator and being provided at its upper end with a cooling fin wholly clearing the insulator and directly exposed to the cooling action of passing air currents, said electrode being made of good heat 55 conducting material solid in cross-section to

permit maximum heat transfer, and being modified from standard practice in that it is relatively short so that the difference in temperature between the electrode at the cooling fin and the surrounding atmosphere is sufficiently great to permit effective cooling.

7. A spark plug comprising a shell provided with the usual side electrode, a central electrode, and an insulator in the shell, the upper end of the insulator being provided with an annular depression surrounding the center wire and providing a rib on the insulator to increase the surface insulation, said central electrode being provided at its upper end with a cooling fin wholly clearing the insulator and directly exposed to the cooling action of passing air currents, said electrode being made of good heat conducting material solid in cross-section to permit maximum heat transfer, and said central electrode being modified from standard practice in that it is relatively short so that the difference in temperature between the electrode at the cooling fin and the surrounding atmosphere is sufficiently great to permit effective cooling.

8. A spark plug comprising a shell having a conical seat between its ends, a central electrode, and an insulator in the shell having a conical lower portion in direct engagement with said seat, the upper end of the insulator being provided with a protuberant rib to increase the surface insulation, said central electrode being provided at its upper end with a cooling fin wholly clearing the insulator and directly exposed to the cooling action of passing air currents, said electrode being made of good heat conducting material solid in cross-section to permit maximum heat transfer, and said electrode being modified from standard practice in that it is relatively short so that the difference in temperature between the electrode at the cooling fin and the surrounding atmosphere is sufficiently great to permit effective cooling.

90. In testimony whereof we affix our signatures.

HECTOR RABEZZANA.
DONALD W. RANDOLPH.
